(57) **CLAIM**

The ornamental design for an access control device, as shown and described.

DESCRIPTION

FIG. 1 is a top, front, right perspective view of an access control device in accordance with our design;

FIG. 2 is a top, rear, left perspective view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear elevational view thereof.

The broken lines represent portions of the access control device in which the design is embodied that form no part of the claimed design. The dash-dot-dot boundary line indicates the bounds of the claimed design and forms no part thereof.
